[57] CLAIM

The ornamental design for a filled bowl brush with cleaner, as shown and described.

DESCRIPTION

FIG. 1 is a front elevational view of a filled bowl brush with cleaner embodying our invention;

FIG. 2 is a side elevational view as seen from the right of FIG. 1;

FIG. 3 is a side elevational view as seen from the left of FIG. 1;

FIG. 4 is a top plan view thereof; and,

FIG. 5 is a rear elevational view thereof.

The broken line showing of bristles is for illustrative purposes only.
